US00D732509S

(12) **United States Design Patent**
Brunner et al.

(10) **Patent No.:** **US D732,509 S**
(45) **Date of Patent:** **** Jun. 23, 2015**

(54) **AUDIO LISTENING SYSTEM**

(71) Applicant: **Apple Inc.**, Cupertino, CA (US)

D299,344 S 1/1989 Stevens
D299,454 S 1/1989 Kwong
D309,306 S 7/1990 Weiser et al.
D316,550 S 4/1991 Sogabe

(72) Inventors: **Robert Brunner**, San Francisco, CA (US); **Rhys Bonahoom**, Burlingame, CA (US)

(Continued)

(73) Assignee: **Apple Inc.**, Cupertino, CA (US)

FIG. 1 is a front perspective view of an audio listening system showing our new design;
FIG. 2 is a rear view thereof;
FIG. 3 is a front view thereof;
FIG. 4 is a right side perspective view of the earbud of an audio listening system showing our new design, shown separately for purposes of illustration;

FIG. 5 is left side perspective view thereof;

FIG. 6 is a rear view thereof;

FIG. 7 is a front view thereof;

FIG. 8 is a right side view thereof; and,

FIG. 9 is a left side view thereof.

The broken lines within the Figures show portions of the audio listening system that form no part of the claimed design.

1 Claim, 4 Drawing Sheets
